216,300

ARMORED VEHICLE

James M. Bemiss, St. Clair Shores, Mich., assignor to
Cadillac Gage Company, Warren, Mich.

Filed June 28, 1968, Ser. No. 12,545

Term of patent 14 years

Int. Cl. D12—13

U.S. Cl. D14—3

Des. 216,300

PAGE 2

FIG. 1 is a perspective view of an armored vehicle, showing my new design;

FIG. 2 is a top plan view;

FIG. 3 is a rear elevational view;

FIG. 4 is a side elevational view; and

FIG. 5 is a front elevational view thereof.

The dominant features of my design reside in the portions shown in full lines.

I claim:

The ornamental design for an armored vehicle, as shown and described.
